UNITED STATES PATENT OFFICE.

RUFUS B. HOOKER, OF STEPHENVILLE, TEXAS.

KNEE-PROTECTOR.

1,309,627.

Specification of Letters Patent. Patented July 15, 1919.

Application filed April 30, 1915. Serial No. 24,980.

To all whom it may concern:

Be it known that I, RUFUS B. HOOKER, a citizen of the United States, residing at Stephenville, in the county of Erath and State of Texas, have invented certain new and useful Improvements in Knee-Protectors; and I do hereby declare the following to be a full, clear, and exact description of the invention, such as will enable others skilled in the art to which it appertains to make and use the same.

This invention relates to knee protectors, designed for use by carpet layers, cotton pickers, carpenters, and other workmen and mechanics, and one of the principal objects of the invention is to provide a knee protector having a spring at one or both ends which will hold the protector pad in place and render the same easy to attach and detach, to and from the leg of the wearer.

Another object of the invention is to provide a knee protector comprising a piece of material open along its edges and having springs connected to the opposite ends of the protector, said springs having outwardly curved ends so that the springs can be readily clasped onto the leg of the wearer and will hold the protector firmly in place, and at the same time permit the movements of the legs with comfort.

The foregoing and other objects may be attained by means of the construction illustrated in the accompanying drawings, in which—

Figure 1 is a view showing the application of the invention,

Fig. 2 is a rear side perspective view of the protector, and

Fig. 3 is a transverse sectional view taken through one of the springs.

Referring to the drawing, the numeral 1 designates a knee protector comprising a

rectangular piece of flexible material of suitable character, and connected to the opposite ends of the knee protector 1 are 45 curved springs 2. The springs 2 are secured to the protector 1 by rivets or suitable fastenings 3. The ends of the springs 2 are curved outwardly as shown at 4, said ends being separated a sufficient distance so that 50 the protector can be readily sprung onto the leg of the wearer, with one spring above and the other below the knee.

From the foregoing it will be obvious that a knee protector made in accordance 55 with this invention can be quickly attached in place on the leg of the wearer, and can be readily withdrawn, while at the same time, the springs will give to the action of the muscles of the legs, and will not be uncomfortable to wear.

Various changes may be made in the details of construction without departing from the spirit and scope of the invention as defined in the claim.

What is claimed is:—

A knee protector comprising an elongated strip of material adapted to be formed into an arcuate tube having a longitudinally extending opening of considerable width in 70 one side thereof, and spring clips adapted to secure the material in tube formation and having their ends spaced to provide an entrance opening coextensive with and alining with the opening in the tube and each clip 75 having its ends curved in a direction away from the opening in the tube to permit the easy application of the protector.

In testimony whereof I affix my signature in presence of two witnesses.

RUFUS B. HOOKER.
